UNITED STATES PATENT OFFICE

102,984

DESIGN FOR A TEXTILE FABRIC

Curt Erwin Forstmann, Montclair, N. J.

Application June 2, 1936, Serial No. 62,956

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design is three-dimensional. It comprises stripes running both warpwise and weftwise, each stripe appearing as a pair of spaced parallel woolly ridges, and at each intersection of the stripes there are four woolly elevated nubs giving the appearance of a square formation. The nubs stand at higher elevations than the ridges, and between the square formation there is an interspersal of irregular smooth finished stitches.

I claim:

The ornamental design for a textile fabric as described and as shown.

CURT E. FORSTMANN.
